UNITED STATES PATENT OFFICE.

AUGUSTINE DAVIS, JR., OF CINCINNATI, OHIO.

MILK-CAN.

1,370,007.

Specification of Letters Patent.

Patented Mar. 1, 1921.

Application filed January 13, 1919. Serial No. 270,851.

To all whom it may concern:

Be it known that I, AUGUSTINE DAVIS, Jr., a citizen of the United States, and a resident of Cincinnati, in the county of Hamilton and State of Ohio, have invented certain new and useful Improvements in Milk-Cans, of which the following is a full, clear, and exact description, reference being had to the accompanying drawings, forming 10 part of this specification.

An object of my invention is to provide a milk can which shall be adapted for the use of the ordinary push-in and umbrella milk can covers and also for a lock cover. The special object of the invention is to provide a lock cover which can be readily and easily secured over the mouth of the can without the necessity for any locking bands or lugs on the can itself, so that a more sanitary 15 can is provided without projections or shoulders on the can to accumulate dirt. Moreover the cover may be locked without twisting or turning. The cover is also designed to be applied on the mouth of the can so 20 that the cover does not have to be applied at any particular point, thus very materially saving wear on the can. A further object is to provide a can where not only curved surfaces are presented, but which can be 25 welded without seams on the inside.

Still further objects and benefits of the construction will be evident from the following description in which the various advantages are pointed out and covered in the 30 claims.

In the drawings which embody the preferred construction of my invention, Figure 1 is a side elevation of my improved can with the cover in place and one side locked.

Fig. 2 is a central vertical section of the same.

Fig. 3 is a side elevation of the can, illustrating its adoption for use with the push-in and umbrella covers.

Fig. 4 is a top plan view with the lock cover in place.

Fig. 5 is an enlarged vertical section of the mouth of the can, with the cover partially locked.

Figs. 6 and 7 are perspective views of the locking device in two positions.

Fig. 8 is a perspective view of the locking arm, with its cam lug.

Fig. 9 is a perspective view of the coöp-

erating cam device which is secured to the 55 cover.

The can itself is made up of three parts assembled together and welded either electrically, or by the oxyhydrogen or oxy-acetylene methods.

The bottom of the can 1 is pressed out of a sheet of suitable sheet metal rounded at the corners, with a slightly upturned flange upon which is welded the cylindrical portion 2 of the can so as to leave a smooth imperceptible joint on the inside, and around the bottom an outside ring 3 is secured, preferably by spot welds 4 so as to form a substantial support for the can.

The breast and neck of the can 5 is formed 70 out of a single piece of sheet metal, with the lower edge of the exact diameter of the cylindrical portion 2, and this joint is welded as in the case of the bottom, and to strengthen the construction and for holding the handles 7, 7, which are secured thereto, a band 6 is welded, preferably by spot welds 8 on the outside of the can. The neck or mouth is preferably formed slightly flaring, and is curled over outwardly and 75 welded to a stiffening ring 9, so as to provide a stiff and substantial mouth for the can, with a bead on the outside.

There are no lugs or projections of any kind around the neck of the can on the outside, and it will be obvious that this construction of can will be adapted to receive the ordinary push-in cover 10, or the umbrella cover 11 as indicated in Fig. 3.

Where it is not desired to use the ordinary push-in or umbrella cover, I provide the lock cover 12. This cover is formed of substantial sheet metal pressed into shape, with the depending flange 13 to fit over the neck of the can.

For locking this cover in place, I provide as follows: Openings 14, 14, are formed on opposite sides of the depending flange and over each of these openings a recessed cam plate 15 is secured, preferably by rivets, in 90 the openings 16. Each cam plate is formed with a central opening 17 and a recessed cam surface 18. Fitted in each recess 17 is an inwardly projecting stud 19 on the lever arm 20. The studs 19 carry cam blocks 21 100 which are formed with cam surfaces 22 to correspond to the cam surfaces 18 in the cam plates. When the cam blocks 21 are in

horizontal position with the lever arms 20 projecting upwardly, the cam surfaces will so fit as to allow the studs 19 to project outwardly, bringing the inner surface 23 of 5 each cam block flush with the inner surface of the flange of the lid. In this position, with the locking levers extending upwardly, the cover can be dropped over the neck of the milk can. Then by turning down the 10 levers or arms 20 into horizontal position, the cam surfaces between the two parts will cause the studs to be drawn inwardly and the cam blocks will be brought forcibly to bear underneath the bead on the outside of 15 the can mouth, and thus the cover will be securely and rigidly locked in the mouth of the can.

The levers 20 are provided with flat portions 24, so that they can be readily and 20 easily pushed down into horizontal position, and as most convenient for manipulation, I prefer to provide that these locking levers shall be turned in an opposite direction. A stop lug 25 projects outwardly for 25 the two cam plates 15 on opposite sides of the studs so as to permit movement only in one direction, and I also provide for each locking lever a corresponding lug 26. These two lugs are pierced with openings 27, 28, 30 which, when the levers are turned down, are brought into registry, so that a seal can be secured through these openings. It will be noted that when the levers are turned down over a horizontal position, they come 35 below the top surface of the cover so that there is nothing to interfere with stacking the cans on top of each other, and the camming operation against the outer bead around the neck of the can forces down the 40 cover so as to give an airtight seal joint for the cover on the can.

Inasmuch as the camming surfaces are on the cover, no lugs or bands are required to secure same to the can, the cover can be 45 dropped into place at any point around the neck of the can, and there is no wear by reason of the necessity of always securing the lid at some definite position. Moreover the lid does not have to be turned or twisted to 50 locate it in proper position, which takes time and ordinarily requires some shifting of position of the user.

Having thus described my invention, what I claim as new and desire to secure by Letters Patent, is:—

55

1. In a milk can provided with an open mouth and beaded rim, a cover therefor, with turning locking pieces on the cover to engage under the rim at any point, said locking pieces being also movable inwardly and outwardly, with cam means for shifting them mounted in the cover, to lock and release the cover from the can.

2. In a milk can provided with an open mouth and beaded rim, a cover therefor and 65 a cam lever pivotally and slidably mounted in the cover, with cam surfaces intermediate the lever and cover, whereby upon rocking the lever it will be drawn into locking engagement with the rim.

70

3. In a milk can provided with an open mouth and beaded rim, a cover therefor and a cam lever pivotally and slidably mounted in the lever, with cam block on the lever and a cam plate on the cover, whereby upon 75 rocking the lever the cam block will be forced under the rim of the can to lock the cover in place.

4. In a milk can provided with an open mouth and beaded rim, a flanged cover for 80 the can adapted to fit down over the rim, with locking levers pivoted in the flange on opposite sides of the cover and movable inwardly, with means for forcing said levers inwardly to engage the rim and lock the 85 cover in place.

5. In a milk can provided with an open mouth and beaded rim, a flanged cover for 90 the can adapted to fit down over the rim, with locking levers pivoted in the flange on opposite sides of the cover, and movable inwardly, said levers and cover being provided with interengaging cam surfaces, whereby the levers will be forced inwardly upon 95 pivotal movement to lock the cover in place.

6. A milk can provided with an open mouth and externally unobstructed neck, and with a reinforced bead at the mouth, whereby the can shall be adapted to receive and hold any of the three types of covers, 100 the bead being adapted to coöperate with cam blocks pressing upward thereagainst.

AUGUSTINE DAVIS, JR.
